UNITED STATES PATENT OFFICE.

KOICHI KAWANO AND RISAKU NISHIMOTO, OF SEATTLE, WASHINGTON.

HOTEL CALL-BELL.

1,125,851.

Specification of Letters Patent.

Patented Jan. 19, 1915.

Application filed April 23, 1914. Serial No. 533,826.

To all whom it may concern:

Be it known that we, KOICHI KAWANO and RISAKU NISHIMOTO, subjects of the Emperor of Japan, residing at Seattle, in the county of King and State of Washington, have invented certain new and useful Improvements in Hotel Call-Bells, of which the following is a specification.

This invention relates to an electric alarm system for use in hotels for awakening or calling guests in the various rooms at predetermined times.

The object of the invention is the perfecting of devices of this character to furnish a better and more reliable call-bell system than hitherto.

The invention consists in the novel construction, adaptation and combination of devices, as will be hereinafter described and claimed.

In the accompanying drawings, Figure 1 is a view in front elevation, and shown somewhat diagrammatically, of a call-system embodying the present invention. Fig. 2 is a section taken on line 2—2 of Fig. 1. Fig. 3 is a detail face view of the commutator shown detached.

The reference letters A, B and C represent electric call-bells which are located in separate guest-rooms of a hotel and are connected to circuit wires a, b and c and also with circuit wires a¹, b¹ and c¹ which are joined, as indicated, to a wire d including a battery D. The aforesaid circuit wires are provided with terminals a², b² and c² in the form of plugs which protrude through coupling blocks k as shown at the right of Fig. 1. Said blocks are of a suitable non-conducting material and, in consequence, the various circuits as so far explained are incomplete. We provide, however, a normally open switch, such as the so-called "push-button," represented by E, E¹ and E², for each of the various circuits so that the latter may, if desired, be manually closed to operate the respective call-bells. Said plugs or terminals a², b² and c² serve as connectors with pairs of bus-rods, as f and f¹, f² and f³, etc., which extend into a switch-board G provided with series of sockets as g, g¹ and g² to receive said plugs and connect the same with selected pairs of the bus-rods. The latter are connected by wires h, h¹, h², etc. with metal rods J, J¹, J², etc., extending through an annular non-conductor M and arranged

in a circle, and constitutes a commutator having, preferably, twenty-four contact elements as shown in Fig. 3.

The apparatus is actuated and controlled by clock-work which is inclosed in a casing 60 secured to the wall in the hotel office or other convenient place. The clock-work may be of any usual or suitable type, but only such parts thereof are illustrated as are deemed requisite for an understanding of 65 the invention.

Disposed axially of said commutator is a post 2 carrying near its outer end a finger 3. Mounted for independent rotary motion upon said post is a toothed gear wheel 4 in 70 continuous mesh with an intermediate gear 5 which is driven from a gear-wheel 6 which is fixedly secured to the arbor 7 carrying the hour-hand 8 of the clock; the hour-hand revolving once every twelve hours and to 75 correspondingly drive the wheel 4 the latter and the wheel 6 are of equal diameters.

Attached to the rear of the gear-wheel 4 is the end of an arm 9, of resilient or spring metal, carrying at its other end a conical 80 block 10 which serves as a contact closer between the successive elements J, J¹, etc.

Juxtaposed with the front of wheel 4 is a crown-cam 11 which is characterized by having upon its outer edge a wiping surface 85 with a portion 12 parallel with the plane of the adjacent face of the wheel 4 and at one side of the cam is provided a recess to afford an inclined surface 13 which extends from the inner end of a shoulder 14 to the plane 90 of the portion 12.

The cam 11 is prevented from rotating by means of a hook 15 engaging in a hole provided in the cam and connected to a link 16 by a pivotal pin 17 to accommodate 95 itself to the axial movements of the cam.

18 represents a helical spring positioned to the rear of gear-wheel 4 and serves to urge the cam against the finger 3. The finger 3 is revolved a number of times at half-hour intervals. To such end, the post 2 has fixedly secured thereto a pinion 19 which is rotated from a gear-wheel 20 upon an arbor 21 driven by a spring provided in the barrel 22. The gear-wheel 20 is provided at diametrically opposite sides with relatively deep gullets 23 and 23¹ and constitutes an escapement wheel. The number of teeth in the escapement wheel circumferentially upon each side and between said 110

gullets is equal to a multiple of the teeth in the pinion 19 as, for instance, three times.

A gear-wheel 24 is mounted on the post 5 2 to drive a spindle 25 through the medium of a pinion 26 which is mounted on the spindle. The latter also carries a regulator wheel 27 having in its periphery two recesses 28 and 28¹ to receive a hooked detent 10 29 extending from an oscillatory shaft 30. Said detent is normally held by a spring 31 against the regulator wheel to engage in a recess in the latter. The detent is, moreover, periodically withdrawn from a recess of the regulator wheel by means of an arm 32 engaging therewith and which is carried by a shaft 32¹ having another arm 33 which is intermittently engaged by spurs 34 and 34¹ extending from diametrically opposite sides of a shaft 35 which is 15 rotated by the clock-work once every hour as, for example, the arbor of the minute-hand 36.

The oscillatory shaft 30 also carries a 25 pallet 37 adapted to arrest the rotation of the escapement wheel 20 when either of the gullets thereof are brought into position to receive the pallet which is shoved therein through the agency of the spring 31. When the pallet enters a gullet, the 30 shaft 30 is sufficiently rotated to allow the detent 29 to enter one of the recesses of the regulator-wheel whereupon the latter is locked.

35 When a spur, 34 or 34¹, engages the arm 33, the shaft 32¹ is turned to cause the arm 32 to push the detent from the regulator wheel thereby releasing the same coincidentally with the withdrawal of the pallet 40 from the escapement wheel, resulting in the latter being rotated by the driving spring to actuate the post which affords motion to the regulator wheel and also to the finger 3.

45 The operation of the invention is as follows: The gear-wheel 4 being rotated each twelve hours, will correspondingly carry the contact closer in an orbital path progressively over the contacts J, J¹, J², etc.

50 At half-hour occurrences and through the instrumentality of a spur 34 or 34¹, the arms 32 and 33 are influenced to swerve the detent 29 from its engagement with the regulator wheel 27 and likewise affect 55 the pallet 37 in its relations to the escapement wheel 20. When the latter is thus disengaged by its pallet, the driving spring within barrel 22 will cause the escapement wheel to make one-half of a rotation when

60 the wheel is reengaged by the pallet. The gear-teeth of said escapement wheel, when operating, will produce three rotations in rapid succession to the post 2, resulting in the finger 3, in traversing the wiping face 65 of the cam 11, pushing rearwardly the

latter accompanied by gear-wheel 4 in opposition to the spring 18 when mounting the inclined portion 13 of the cam-face, and retain the cam and the gear-wheel in such rearmost position until the shoulder 70 14 of the cam passes the finger in each rotation. As the shoulder passes the finger, the spring 18 asserts its power to push the gear-wheel 4 and the cam outwardly. By reason of the contact closer 10 being attached to the gear-wheel it will be moved axially of the latter into and out of contact with the adjacent rods or terminals, as J¹ and J², for example, at approximately eight o'clock. When the closer is thus 80 brought into contact with the referred to rods, the plugs of any of the call-bell circuits which are inserted in the sockets, as g⁴ and g⁵, of the bus-rods which are connected with the rods J¹ and J², such circuit 85 or circuits will be closed and opened three times to have connected call bells intermittently ring. The plugs would be placed in the appropriate sockets to have the bells rung at times directed by the guests. 90

What we claim is—

1. The combination with a plurality of electric bells, normally incomplete circuits therefor, an electrical switch, clock-work for periodically rotating said switch, and a 95 spring acting to retain said switch in open position with respect to the terminals of the aforesaid circuits, of a cam, and means actuated by said clock-work and co-operating with said cam for effecting axial movements to said switch whereby the latter is actuated at periods to successively close the gaps between the circuit terminals. 100

2. The combination with a plurality of electric bells, normally incomplete circuits 105 therefor, an electric switch, and a spring tending to maintain said switch in open position with respect to the terminals of the aforesaid circuits, of clock-work for periodically rotating said switch, and means actuated by said clock-work for periodically actuating said switch with respect to the terminals of each of said circuits. 110

3. The combination with a plurality of electric bells, normally incomplete circuits 115 therefor, and clock-work, of a rotary device having axial movement in operative engagement with said clock-work, an electrical switch carried by said device, electrical conductors, means provided on the 120 aforesaid incomplete circuits to couple the same with selected ones of said conductors, and means actuated by said clock-work to effect the axial movement of said rotary device so as to cause the switch to be influenced at periods to repeatedly close the circuits when the latter are coupled with the respective conductors. 125

4. The combination with a plurality of electric bells, normally incomplete circuits 130

therefor, and clock-work, of a rotary device having axial movement in operative engagement with said clock-work, an electrical switch carried by said device, electrical conductors, means provided on the aforesaid incomplete circuits to couple the same with selected ones of said conductors, and means actuated by said clock-work to actuate said rotary device so as to cause the switch to be influenced to successively close the circuits when the latter are coupled with the respective conductors.

5. The combination with a plurality of electric bells, normally incomplete circuits therefor, conductors arranged in pairs and adapted to be interchangeably employed as extensions to the wires of said circuits, an

electrical switch, a spring acting to retain said switch in open position with respect to the terminals of said conductors, and clock- 20 work for rotating said switch into positions to be operable with respect to the successively adjacent conductors, of means also actuated by said clock-work for causing the switch at definite intervals of time to successively bridge the gap between the respective pairs of conductors. 25

Signed at Seattle, Wash., this 17th day of April 1914.
